(57) CLAIM

The ornamental design for a portable storage shelter for diving equipment, as shown and described.

DESCRIPTION

FIG. 1 is an isometric view of a portable storage shelter for diving equipment showing my new design.

FIG. 2 is a front view thereof.

FIG. 3 is a top plan view thereof.

FIG. 4 is a left side view thereof.

FIG. 5 is a right side view thereof.

FIG. 6 is a rear view thereof; and,

FIG. 7 is a bottom plan view thereof.

Broken lines indicating stitching in FIGS. 1 and 3-7 form a part of the claimed design. Phantom lines in FIG. 3 are included for illustrative purposes only and form no part of the claimed design.

1 Claim, 7 Drawing Sheets

FIG. 1

FIG. 2

FIG. 3

FIG. 4

FIG. 5

FIG. 6

FIG. 7
